CAMPING TRAILER

Richard I. Carroll, 1726 E. 1st Ave.,
Mesa, Ariz. 85204

Filed Feb. 1, 1971, Ser. No. 111,805

Term of patent 14 years

Int. Cl. D12—10

U.S. Cl. D14—3

FIG. 3

FIG. 2

FIG. 1

FIG. 4

FIG. 6

FIG. 5

FIG. 1 is a perspective view looking from the rear of a camping trailer showing my new design;

FIG. 2 is a side view of the camping trailer shown in FIG. 1;

FIG. 3 is a top view of the camping trailer shown in FIG. 2;

FIG. 4 is a rear view of the camping trailer shown in FIG. 1-3 with the top of the trailer and side door shown closed;

FIG. 5 is a rear view of the camping trailer shown in FIG. 4 with the top of the trailer and a side door shown in open position; and

FIG. 6 is a front view of the camping trailer shown in FIG. 1.

I claim:

The ornamental design for a camping trailer, as shown and described.
